UNITED STATES PATENT OFFICE.

FRANKLIN P. BATES, OF SYRACUSE, NEW YORK, ASSIGNOR OF ONE-HALF
TO ELLIS L. BAKER, OF SAME PLACE.

DIE FOR MAKING FIFTH-WHEELS.

SPECIFICATION forming part of Letters Patent No. 338,217, dated March 16, 1886.

Application filed July 30, 1885. Serial No. 173,037. (No model.)

To all whom it may concern:

Be it known that I, FRANKLIN P. BATES, of Syracuse, in the county of Onondaga, in the State of New York, have invented new and useful Improvements in the Manufacture of Fifth-Wheels for Vehicles, of which the following, taken in connection with the accompanying drawings, is a full, clear, and exact description.

10 This invention consists in a novel construction of metal dies by means of which fifth-wheels of vehicles are formed in their requisite circular or segmental outline longitudinally and in proper shape in cross-section in the most 15 accurate, perfect, and expeditious manner.

15 The invention is fully illustrated in the annexed drawings, wherein Figure 1 is a top plan view of the female die. Fig. 2 is an enlarged transverse section of the dies, taken on line xx , Fig. 1, and including the support of 20 said dies. Fig. 3 is a longitudinal section of the female die, taken on line yy , Fig. 1. Fig. 4 is a perspective view of the fifth-wheel; and Fig. 5 is an enlarged transverse section taken 25 on line zz , Fig. 4.

25 Similar letters of reference indicate corresponding parts.

30 A represents the female die, consisting of a metal block, which has an annular or segmental face, f , of a true and uniform plane, and is provided in said face with a circular or segmental groove, a , which is of the same diameter and of the same form in cross-section as the wheel to be formed by said die. In said 35 groove, at opposite sides of a diametrical line drawn through the center, about which the groove is formed, are sockets $b b$, for the reception of the clips $i i$, which are usually formed on the under side of the fifth-wheel, as represented in Fig. 4 of the drawings. Said 40 die and its groove a may be either segmental, as represented by full lines in Fig. 2 of the drawings, or circular in form, as indicated by dotted lines in said figure, according to the style 45 of the fifth-wheel to be formed. This die is secured to the supplementary bed B , mounted on the bed proper of a drop-press, which bed is provided with a recess, r , in which the die A is seated and firmly secured by keys w , or other 50 suitable or well-known means.

Between the sockets $b b$ in the die A is a vertical channel, c , extending through the

die, and directly under said channel and coinciding therewith is a vertical channel, e , in the bed B . Said channel e intersects a lateral 55 or horizontal channel, h , extending to the exterior of the bed B , and in this lateral channel h is fulcrumed a lever, l , one end of which protrudes at the exterior of the bed B , so as to be convenient of access for manipulation. 60 Upon the inner end of said lever rests a plunger, d , which projects through the vertical channels e and c .

C represents the male die arranged over the die A , and provided on the side adjacent 65 thereto with a corresponding annular or segmental face of a true and uniform plane.

The operation of my invention is as follows: The fifth-wheel having been previously forged with the attaching clips $i i$, and bent approximately into its requisite segmental or circular shape, is heated to a swaging or forging heat and then placed in the groove a of the die A , the clips $i i$ entering the channels $b b$ of the die. Then the die C , which is attached 70 to the drop of the press, is allowed to drop onto the aforesaid fifth-wheel, thereby effectually pressing the latter into the groove a , which imparts to it its requisite outline longitudinally and transversely, the arrangement 75 of the channels $b b$ in the die A insuring the accurate disposition of the clips $i i$, for attachment to the head-block of the vehicle. After this is effected the die C is raised from the die A , then by depressing the outer ends of 80 the levers $l l$ the plungers $d d$ are caused to throw the fifth-wheel out of the groove a .

It will be observed that by my invention I am enabled to produce fifth-wheels of uniform diameters and perfectly true in outline—a 85 desideratum which has never been accomplished by the method of bending said wheels in the manner heretofore resorted to.

Having described my invention, what I claim as new, and desire to secure by Letters Patent, 90 is—

1. A die for forming fifth-wheels of vehicles, consisting of a metal block having an annular or segmental face of a true uniform plane, and provided in said face with a circular or segmental groove, the diameter and cross-section of which is of the exact dimensions and shape required of the wheel to be formed, substantially as set forth.

2. The within-described dies for forming fifth-wheels of vehicles, consisting of a metal block having an annular or segmental face of a true uniform plane, and provided in said 5 face with a circular or segmental groove of the diameter and cross-section required of the wheel to be formed, and a metal block over said grooved block and provided on the side adjacent thereto with a corresponding annular 10 or segmental face of a true and uniform plane, substantially as described and shown.
3. The dies for forming fifth-wheels of vehicles, consisting of the block A, having an annular or segmental face, f, of a true uniform 15 plane, and provided in said face with the circular or segmental groove a, and with sockets b b in said groove, at opposite sides of a diametrical line drawn through the center about which the groove is formed, and the block C 20 over the block A, and provided on the side adjacent thereto with a corresponding annular or segmental face of a true and uniform plane, substantially as shown and set forth.
4. The combination of the die A, provided 25 with the annular or segmental groove a and the vertical channels c c through the die and

intersecting the groove a, and plungers d d in the channels, substantially as described and shown, for the purpose set forth.

5. The combination of the bed B, provided 30 with a recess, r, vertical channels e e, intersecting said recess, and lateral channels h h, extending from the vertical channels to the exterior of the bed, the levers l l in the channels h h, the die A, seated in the recess r and 35 provided with the annular or segmental groove a, and with vertical channels c c, coinciding with the channels e e and intersecting the groove a, and the plungers d d in said vertical channels and resting on the levers l l, substantially as described and shown, for the purpose set forth.

In testimony whereof I have hereunto signed my name and affixed my seal, in the presence of two attesting witnesses, at Syracuse, in the 45 county of Onondaga, in the State of New York, this 18th day of July, 1885.

FRANKLIN P. BATES. [L. S.]
